5 Claims. (Cl. 117—2)

This invention relates to improvements in methods and means for sealing leaks in oil storage tanks, or the like, and for protecting tank walls against deterioration in service. More particularly, the invention provides a method and means for permanently sealing any hole or holes that may have developed in lower wall portions of an oil storage tank, or the like, or for permanently protecting said lower wall portions against corrosive deterioration, the said sealing and protecting being effectively accomplished without need for emptying the tank of oil, or other liquid.

The present application is a continuation-in-part of our applications Serial No. 348,211, filed April 13, 1953, and Serial No. 423,489, filed April 15, 1954, entitled Method and Means for Renovating Corrosion-Deteriorated Tanks, both now abandoned.

Oil storage tanks of the conventional sheet metal varieties are subject to deterioration in service due to corrosion resulting from moisture which unavoidably gets into the tanks in relatively small amounts and condenses on lower wall portions thereof. Moisture in relatively small amounts ordinarily is present in oil delivered into the storage tanks and tends to settle and condense interiorly of the tank walls. Deterioration of the tank walls, due to corrosion, is a relatively slow process and a tank may serve its purposes for eight, ten, twelve, or more years, before the ravages of corrosion ultimately produce one or more leak holes in the tank walls.

Heretofore, an oil tank whose walls have deteriorated to a condition in which oil leaks from the tank through a hole or holes eaten by corrosion through the tank walls ordinarily would be condemned as unfit for further extended service. Sometimes such a leak has been temporarily sealed or patched to stop the leakage of oil until such time as the old tank might be replaced by a new one but, so far as we are aware, no prior sealing or patching procedure has contemplated restoration of a leaky tank to a condition in which it could render extended further service without danger of recurrence of the old leaks or development of new leaks.

Leaks in oil storage tanks, due to corrosion, develop only at lower wall portions of the tanks because moisture within the tank settles and condenses predominantly on the lower or bottom portions of the tank walls. For example, corrosion-induced leaks in oil tanks of the cross-sectionally curved-bottom types develop only in a relatively narrow band extending longitudinally along the bottom of the tank. Long experience indicates that substantially all such leaks develop within a band from four to five inches wide because such moisture as may be present within any such tank tends to settle and condense within this relatively narrow band of bottom wall. Hence, when corrosion causes such a tank to leak, it may be fairly assumed that the corrosive deterioration of the tank walls will be substantially confined to the mentioned band along the tank bottom and that other portions of the tank walls continue in serviceable condition. The invention pro-

vides a method and means whereby a leaky tank not only may be permanently sealed at the leak or leaks but may be conditioned for further long service without danger that new leaks will develop, and it is of considerable importance that the mentioned sealing and conditioning may be accomplished while the tank continues filled or partially filled with oil and without substantial loss of oil during the sealing and conditioning process.

Hence, it is among the objects of the invention to provide a method of permanently sealing leak-holes in bottom wall portions of filled or partly filled oil tanks, and the like, while simultaneously insuring against any subsequent development of corrosion-induced leak-holes within a predetermined band of bottom wall extending from end to end of any particular tank.

Another object of the invention is to provide a method of permanently sealing leak-holes in oil storage tanks, and the like, while simultaneously permanently protecting a predetermined band of bottom wall of the tank against subsequent development of leak holes due to corrosion.

A further object of the invention is to provide a renovated oil storage tank, or the like, wherein the predetermined band of bottom wall of the tank, extending from end to end of the tank, has an adhered protective covering thereon permanently sealing the said band of bottom wall against moisture from within the tank and also sealing any leak-hole or leak-holes that may have been present in the tank bottom wall within the said covered band.

Yet another object of the invention is to provide a renovated oil storage tank, or the like, wherein a mixture of fibrous material and cement deposited into a filled or partially filled tank is distributed as an adhered protective covering over a predetermined band of bottom wall of the tank permanently sealing said covered band of wall against any deteriorating effects of moisture which may be present within the tank, the cement in the said covering mixture providing a permanently stable protective covering having the property of absorbing and harmlessly consuming moisture from the interior of the tank.

Still another object of the invention is to provide a tank-renovating method whereby a corrosion-deteriorated oil storage tank, or the like, may be restored for a further long life of service without need for emptying the tank but with the contents of the tank serving to float a deposited mixture into covering relation to a predetermined band of bottom wall of the tank, and with the materials of said mixture providing a stable adhered protective covering over said band of bottom wall permanently sealing the covered band against any deteriorating effects of moisture which may be present within the tank, the said tank contents and said mixture coating to effect a sealed plugging of any leak-hole or leak-holes that may have been present in the said band of bottom wall of the tank.

The mentioned objects and results may be attained by depositing suitable materials, including a relatively large amount of Portland cement or the like, into the tank which is to be renovated or protected against corrosive deterioration, the said materials being adapted to provide an adhered and stable protective covering over a predetermined band of the tank bottom wall, from end to end of the tank, thereby to permanently seal said band against the ravages of corrosion, and to expose a body of cementitious material to direct contact with the oil, or other liquid, for absorbing and consuming moisture from the oil.

In the case of a tank having corrosion-developed leak-holes, the leak-holes may, if desired, be enlarged and plugged from the exterior of the tank prior to deposition

within the tank of the materials for sealed protective covering of the mentioned band of tank bottom wall. Preferably, however, any leak-holes in a tank bottom wall are plugged from within the tank by the material deposited in the tank, some of said material being carried into plugging relation to any leak-hole by the oil or other liquid initially escaping through the leak-hole. The subsequent build-up of the sealing protective covering over said band also permanently seals the plugged leak-hole which, if desired, may be subsequently plugged exteriorly of the tank to provide a finished exterior appearance.

In the accompanying drawings:

Fig. 1 is a vertical cross-sectional view through a conventional variety of home fuel oil storage tank having an adhered protective covering body of material covering and sealing a substantial width of the tank bottom wall against deteriorating effects of corrosion;

Fig. 2 is a cross-sectional view on line 2—2 of Fig. 1;

Fig. 3 is a fragmentary cross-sectional view of the lower wall portion of the tank of Figs. 1 and 2, on a larger scale, and prior to deposition in the tank of the sealing and covering material of Figs. 1 and 2;

Fig. 4 is a view generally similar to Fig. 3 but showing the deposited material settling through the oil, or other liquid, and being carried by the escaping liquid into plugging relation to a leak-hole in the bottom wall of the tank;

Fig. 5 is a view generally similar to Figs. 3 and 4 but showing the deposited material covering a substantial width of the bottom wall of the tank and also covering the plugged leak-hole therein;

Fig. 6 is a view similar to Fig. 5 but showing the interiorly sealed leak-hole exteriorly plugged by a screw plug; and

Figs. 7-11 are views generally similar to Fig. 3 but showing successive steps in a modified form of the invention in which a leak-hole may be exteriorly plugged prior to deposition of the sealing and protective material within the tank.

Generally, the following disclosure contemplates applying to an area of the inner surface of a metallic, e.g. steel, oil-tank, without removing the oil therefrom, an aqueous cementitious material whose characteristic ingredient is selected from the class consisting of inorganic silicon compounds and inorganic calcium compounds. It has been found that such a material, which has greater density than the oil through which it is applied, is capable of adhering to and solidifying upon the inner surface of the tank, notwithstanding the presence of the oil, in order to provide a coating that seals leaks and prevents corrosion.

Referring to the drawings, a conventional variety of oil storage tank 10 is represented in Figs. 1 and 2 partially filled with oil 12. According to the invention a predetermined band or bottom wall, extending from end to end of the tank, is covered by a body of material indicated generally at 14, which is adhered to the bottom wall as a permanent covering which effectively seals the covered area of bottom wall against deteriorating effects of corrosion.

The bottom wall of the tank 10 may have developed a leak-hole or a number of leak-holes as a result of corrosion, and Fig. 3 illustrates a small leak-hole 16 and shows also a region at 18 where the metal has been substantially reduced in thickness by corrosion.

Such a leaky tank, or a deteriorated tank which not yet has reached the leaky stage, or even a new tank, may, according to the invention, be renovated for further long and useful service, or permanently protected against the ravages of corrosion, by deposition into the tank of a mixture of materials in quantity to settle as an adhering stable body covering the mentioned band of bottom wall in a manner to permanently exclude moisture from coming into contact with the covered area of bottom wall.

According to the invention, siliceous cementitious materials and fibrous material are mixed together and with water to provide a flowable mixture which, when poured

into an oil-containing tank 10, settles through the oil 12 and accumulates on the bottom wall of the tank. Pouring of the mixture is continued until the accumulation on the bottom wall spreads and builds up sufficiently to completely cover a predetermined relatively narrow critical band of bottom wall extending from end to end of the tank, after which the accumulation sets to provide a rigid fibre-reinforced mass 14 strongly adhering to the covered wall portions of the tank, sealing out all moisture.

10 The siliceous cementitious material may be Portland cement, or the like, and the fibrous material may be asbestos fibre, preferably, for the most part, relatively coarse and long fibres. However, we have found that the fibres lodge in and plug leak-holes more rapidly and effectively if they are coated or partially coated with adhering cement which also has a grouping effect on the fibres. The cement adhering to the fibres aids and hastens settling of the fibres through oil in the tank, and the grouped fibres can more readily lodge in and plug relatively large leak-holes, as compared with fibres not coated with the cement.

In what we presently consider to be a preferred procedure, a lime-silica or lime-clay cement, in an extremely fine dry powder state, is thoroughly pre-mixed with the 25 asbestos fibre to provide a preliminary dry mixture in which the cement powder constitutes from 40% to 60% of the mixture. This preliminary dry mixture next may be thoroughly mixed with siliceous material of the Portland cement variety, in approximately the proportions of 30 four parts Portland cement to one part of the preliminary mixture, with water added sufficient to provide a readily pourable wet mixture approximating the consistency of heavy cream.

The fine powdered cement in the preliminary dry 35 mixture becomes intimately associated and intermingled with individual fibres and with matted or intertwined groups of the fibres. During the final mixing with Portland cement and water, considerable amounts of the water-activated lime-silica or lime-clay cement adheres 40 to the fibres and groups of fibres. As the ultimate mixture is poured into an oil-containing tank 10, it readily settles through the oil 12. Pouring of the mixture is continued until an accumulation builds up on and spreads over the bottom wall sufficient to completely cover the 45 predetermined band of bottom wall which is to be sealed against corrosive deterioration. The mixture is of a nature to set to substantial hardness while immersed in oil, and the lime-silica or lime-clay cement and the Portland cement cooperate in effecting a relatively strong 50 adhesive bond between the cementitious mass 14 and the tank walls, sealing out all moisture. The water content of the poured mixture becomes absorbed and consumed by the Portland cement which subsequently absorbs such relatively small amounts of moisture as may 55 get into the tank. The fibre in the set mass minimizes cracking or pulling away from the tank walls due to expansion and contraction of the mass and tank. This is especially true when oil 14 in the tank 10 constantly covers the cementitious mass 14, a condition which ordinarily prevails because the cementitious mass may be entirely below the outlet from the tank.

60 It is a characteristic of the cementitious mass 14 that, when it has set, its top surface which is exposed to the oil 12 is flat and smooth, presumably due in some measure to the pressure of oil thereon during the setting process. The smoothness of this top surface, which is subjected to the effects of any turbulence of the oil within the tank, minimizes the likelihood of fragments of the cementitious mass becoming detached and floated away 65 in the oil. However, it is recommended that a suitable filter be provided in the flow passage between the tank and the oil burner to ensure against the possibility of particles of the poured mix or of the ultimate protective mass being carried through the oil feed line to the burner.

If there is a leak-hole in the bottom wall of a tank which is being renovated, such as the hole 16 shown in Fig. 3, oil will be escaping therethrough, and some of the poured mixture initially will be carried with the oil through the leak-hole until fibres, adhesively grouped or otherwise, lodge and accumulate in the hole and relatively quickly plug the hole against all but a mere seepage of oil. The subsequent accumulation of the poured mixture covers the plugged hole 16, preventing any further leakage or seepage of oil through hole 16 after the mass 14 has set in sealed attachment to the tank walls. Fig. 4 shows fibres of the poured mixture accumulated in leak-hole 16, and Fig. 5 shows the built up cementitious mass 14 covering bottom wall portions of the tank and covering the plugged leak-hole 16.

The fibre-plugged leak-hole 16, when desired, may be suitably enlarged exteriorly of the tank for reception of a screw plug, or the like, to provide a finished exterior appearance. Fig. 6 shows such an exteriorly applied screw plug at 20. Plug 20 ordinarily will be put in place while the poured interior mixture continues in a relatively fluid or plastic condition and the plug becomes locked and sealed by the interior mixture when the latter sets. Or, the plug 20 may be screwed into place after the interior mixture has set, the fibre re-inforced interior mass, following complete setting thereof, being of a nature to receive the screw plug 20 without cracking.

Commercially available preparations of asbestos fibre and lime-silica or lime-clay cement conveniently may be utilized for the preliminary mixture earlier described herein. A dry preparation available under the name "Insulag" and put out by Quigley Co., Inc., of 527 Fifth Avenue, New York, N.Y., and a dry preparation available under the name "Stic-tite" and put out by Refractory & Insulation Corp., of 120 Wall Street, New York, N.Y., may be employed to provide our preliminary mixture of asbestos fibre and lime-silica or lime-clay cement. Analysis indicates that "Insulag" consists of approximately one part asbestos fibre to four parts lime-silica or lime-clay cement, and that "Stic-tite" consists of approximately one part lime-silica or lime-clay cement to four parts asbestos fibre. The cement in each preparation consists of approximately one part lime to four parts silica or clay. These available dry preparations may be mixed together in approximately the proportions of one part "Stic-tite" to three parts "Insulag" to provide a preliminary dry mixture containing a little less than two parts cement to one part asbestos fibre. In the "Insulag" preparation, the fibres, to a considerable extent, tend to be matted or intertwined, or otherwise joined, into relatively small groups of fibres with a relatively large amount of finely powdered cement intimately associated therewith, which makes this preparation generally coarser than the "Stic-tite" preparation wherein the fibres do not become grouped to any notable extent, and wherein there is a relatively smaller amount of the cement powder. These differences in the two preparations are advantageous in the ultimate pourable mixture in that the grouped fibres more readily become lodged in fairly large leak-holes and the relatively individually free fibres more effectively can enter and lodge with others to plug smaller leak-holes and cracks.

Figs. 7-11 illustrate a modified tank-renovating procedure wherein any leak-hole in the bottom of a tank may be initially plugged from the exterior of the tank prior to deposition in the tank of the materials for protectively covering the predetermined band of tank bottom wall. Assuming that a tank has a small leak-hole as indicated at 16 in Fig. 3, the hole may be drilled to a larger size, as at 30 in Fig. 7, for reception of a relatively soft rubber plug 32 which is shown in Fig. 7 ready to be thrust into the enlarged hole 30. Oil gushes out through the enlarged hole until plug 32 is in place, as in Fig. 8, stopping all but a slight seepage past the plug. But the oil quickly acts on the soft rubber plug with deteriorating

effect and causes substantial swelling of the plug which relatively quickly takes the general form as represented in Fig. 9. It is essential that deterioration of the rubber plug be arrested before the plug becomes decomposed to a degree which would destroy its effectiveness as a plug, and this may be accomplished by deposition in the tank of material which spreads over the bottom of the tank, as described in connection with Figs. 1-6, and over the rubber plug as in Fig. 10. The deposited material may be the same mix which forms the protective body 14 in the Figs. 1-6 embodiment, in which case the body 14 effectively seals the plugged hole against entrance of any additional oil to the rubber, as well as sealing the covered band of tank bottom wall against corrosive deterioration, as described in connection with Figs. 1-6. Or water glass 34 may be first deposited in the tank to provide a sealing coating over the plug and over the tank bottom area which is to be protected, followed by deposition of Portland cement to provide a stabilizing protective body 14' over the water glass 34, in Fig. 11.

It should be understood that the invention, in its broader aspects, provides a tank-renovating procedure and method wherein any of a variety of inorganic siliceous, cementitious materials, having specific gravity greater than that of an organic liquid stored in a metal tank, may be poured into the filled or partially filled tank to renovate the tank while it continues to be filled or partially filled with oil, or other liquid. The poured material preferably will be mineral aqueous cementitious material, suitable examples of which are Portland cement, Atlas cement and Keene's cement with water added sufficient to give the cement the consistency of relatively heavy cream.

The pourable material in some cases, such as when a tank has no relatively large leak-holes, may consist entirely of one of the mentioned mineral aqueous cementitious materials, rendered pourable and settable by addition of a suitable amount of water. When fibres are omitted from the pourable material, some cracking of the protective body may occur in the setting process, but minor cracks, apparently, do not effect the effectiveness of the protective mass, presumably because the cement tends to absorb and consume moisture which otherwise might condense on the tank walls. Neither do such minor cracks materially increase the likelihood of fragments becoming loosened or broken away from the mass as a result of turbulence of oil in the tank, especially when the oil inlet pipe is equipped with a spray nozzle as indicated at 11 in Figs. 1 and 2, such a nozzle 11 being recommended in all cases to avoid concentration of a stream of incoming oil at any one location. Nozzle 11 relatively gently sprays the incoming oil with no substantial created turbulence within the tank.

Addition of fibre to the cement usually will be found desirable, inasmuch as the fibres initially lodge in leak-holes and cracks to effect plugging thereof before the poured material accumulates on the tank wall portions and ultimately sets in adhered covering relation to the mentioned predetermined band of bottom wall which becomes permanently sealed against corrosive deterioration. Also, the fibres strengthen the cementitious mass, minimizing any tendency of the material to crack or pull away from the tank walls. If the fibres are mixed directly with the siliceous cement and water when preparing the pourable mixture, the fibres preferably should be asbestos fibres, or comparable mineral fibres of a nature to settle through oil. On the other hand, if the fibres are pre-mixed with lime-silica or lime-clay cement to provide a preliminary dry mixture as earlier described herein, other varieties of fibres may be employed, such as vegetable fibres because the fibres of this preliminary mixture become coated or partially coated with the lime-silica or lime-clay cement when the latter is activated by the water in the ultimate mixture, and the adhering cement causes

the fibres to settle through the oil and they can serve the functions described in connection with asbestos fibres.

It is intended that the patent shall cover, by suitable expression in the appended claims, whatever features of patentable novelty exist in the invention disclosed.

We claim as our invention:

1. The method of coating an inner bottom surface area of the walls of a generally cylindrical horizontally disposed oil-containing tank, comprising the steps of predetermining a relatively narrow band of bottom wall of the tank within which band substantially all corrosive deterioration of the tank occurs, depositing through a top opening in the tank an aqueous cementitious material in quantity to cover said predetermined band by settling through the oil in the tank, said deposited material containing a mixture of lime-clay cement and fibres and to which has been added in aqueous mixture a compound from the class consisting of compounds of silicon and calcium, the said deposited material being of a nature to settle through the oil in the tank into protective covering relation to said predetermined band of tank bottom wall, and letting all of the band-covering deposited material set to substantial rigidity while immersed in said oil.

2. The method of renovating an oil tank which has developed leak holes as a result of corrosive deterioration comprising predetermining a relatively narrow horizontally extending critical band of tank wall wherein substantially all said corrosive deterioration of the tank will occur, preparing an aqueous mixture of a fibrous material and a cementitious material having greater density than the oil in the tank, settling said mixture through the oil whereby said fibrous material floats to and lodges in and substantially to plug the leak-holes, continuing the settling of the material until a substantial accumulation thereof covers only slightly more than said predetermined critical band and said leak-holes, and letting all of the band covering accumulation set in the presence of said oil to provide a stable, substantially rigid covering over said critical band and said leak-holes.

3. The method of renovating a generally cylindrical horizontally disposed oil-containing storage tank susceptible of corrosive deterioration producing leak-holes in a lower wall portion thereof, comprising predetermining that relatively narrow longitudinally extending band of tank wall wherein substantially all said corrosive deterioration will occur, providing a pourable aqueous mixture of a mineral cement and a lime-silica compound interspersed with fibrous material and having specific gravity greater than that of the oil in the tank, pouring said mixture into the tank thereby causing the mixture to settle through the oil and accumulate on said lower wall portions of the tank, a relatively small amount of said poured mixture being initially carried through said leak-holes by escaping oil until fibres in the mixture lodge in and effectively plug the leak-holes, continuing the pouring until said accumulation builds up on and spreads over only slightly more than the total area of said predetermined band of tank wall including said fibre-plugged leak-holes, said poured mixture being of a nature to relatively strongly adhere to the covered wall portions of the tank and to set into a relatively rigid fibre-reinforced cementitious body protectively sealing said covered band of wall against corrosive deterioration.

4. The method of renovating an oil-containing storage tank as defined in claim 3 wherein the said fibres are pre-mixed with finely powdered lime-silica cement in a dry state to provide a dry preliminary mixture in which the powdered cement constitutes from 40% to 60% of the dry mixture, the said pourable aqueous mixture consisting of approximately one part of the said preliminary dry mixture and four parts of the said mineral cement.

5. The method of renovating a generally cylindrical horizontally disposed oil-containing storage tank having a leak-hole in a lower wall portion thereof, comprising predetermining a relatively narrow horizontally extending band of tank wall wherein substantially all corrosive deterioration of the tank will occur, pre-mixing finely powdered lime-clay cement in a dry state with fibres to provide a dry preliminary mixture in which the powdered cement constitutes from 40% to 60% of the dry mixture, whereby the cement powder becomes intimately associated and intermingled with the fibres, followed by thoroughly mixing approximately one part of the said preliminary mixture with approximately four parts of settable siliceous cement, and water sufficient to provide a pourable mixture having substantially the consistency of heavy cream, and then pouring the latter said mixture into the tank through a top wall opening whereby the poured mixture settles through the oil and accumulates on lower wall portions of the tank, some of the settled mixture being carried by leaking oil into and through the said leak-hole until fibres in the mixture lodge in and substantially plug the leak-hole, the said intimacy of association of the cement and fibres in said preliminary mixture resulting in substantial amounts of the pre-mix cement becoming intimately adhered to the fibres when the cement is activated by said water, whereby settling of the fibres is aided by the adhering cement which also tends to unite fibres in relatively small groups which facilitate the said lodging of fibres in the leak-hole, the pouring of the mixture into the tank being continued until the accumulation thereof has built up on and spread over only slightly more than the total area of said predetermined band including the portion thereof in which said leak-hole is located, and all of the said accumulation being allowed to set within the oil to substantial rigidity in adhering sealed relation to the said band of tank wall bottom wall portions of the tank.
